(57) **CLAIM**

The ornamental design for a monster toy, as shown and described.

DESCRIPTION

FIG. 1 is perspective view of a monster toy showing our new design;

FIG. 2 is a front elevation view of the toy of FIG. 1;

FIG. 3 is a rear elevation view of the toy of FIG. 1;

FIG. 4 is a left elevation view of the toy of FIG. 1;

FIG. 5 is a right elevation view of the toy of FIG. 1;

FIG. 6 is a top elevation view of the toy of FIG. 1; and,

FIG. 7 is a bottom elevation view of the toy of FIG. 1.

The broken lines depicted in the drawings show use in an environment only and form no part of the claimed design.
